UNITED STATES PATENT OFFICE.

GABRIEL IOCHUM, OF PARIS, FRANCE, ASSIGNOR OF ONE-HALF TO LÉON JOSEPH GUITARD, OF PARIS, FRANCE.

ROTARY EXPLOSION-ENGINE.

1,033,701.

Specification of Letters Patent. Patented July 23, 1912.

Application filed October 30, 1911. Serial No. 657,625.

To all whom it may concern:

Be it known that I, GABRIEL IOCHUM, a citizen of the Republic of France, residing at 34 Rue des Martyrs, Paris, France, have 5 invented new and useful Improvements in Rotary Explosion-Engines, of which the following is a specification.

This invention relates to a rotary reversible, valveless explosion engine of an 10 extremely light construction having a plurality of compound cylinders arranged with their axes parallel to the axis of rotation.

In the motor according to my invention the central shaft is fixed and about this 15 shaft revolve a number of cylinders in which pairs of pistons reciprocate. Suction and explosion take place in the middle of the length of the cylinders between the pistons, while exhaust takes place through 20 ports which are opened at the end of the stroke of the pistons at the two extremities of each cylinder. The two pistons working in each cylinder move simultaneously in opposite directions, that is, either from the 25 center of the cylinder toward its ends, thus moving away from each other during one stroke, or from each end of the cylinder toward the center thereby approaching each other during the next stroke. The number 30 of cylinders can be varied according to circumstances.

The accompanying drawings represent by way of example, a motor constructed according to my invention having eight compound 35 cylinders having double pistons.

Figure 1 is a side elevation, partly in section along the axis of the motor. Fig. 2 is an end elevation, partly in section along the line *w-w* and in part along line *x-x*, 40 Fig. 1. Fig. 3 is a cross-section partly along line *y-y* and partly along *z-z* Fig. 1. Fig. 4 represents a detail, in section along line *u-u*, Fig. 2, of the valves of the oil pump.

45 *a* represents the central fixed shaft of the motor, each end of which is intended to be held by a suitable support according to the purpose for which the motor is intended, which latter rests only upon the ends of said 50 shaft. On the shaft *a* are keyed at *b* two bevel wheels *b*¹, each of which is held fast by a collar *b*² which abuts against a shoulder on the shaft in order to avoid any displacement. Bevel wheels *c* roll upon each of the

bevel wheels *b*¹ and in the present case of a 55 motor having eight compound cylinders they are eight in number and are supported by brackets *d* consisting of radial arms starting from the center and equal in number to the cylinders, so as to form a number of divisions or compartments about the central shaft *a* equal to the number of cylinders. These arms *d* are strengthened by cross bars *d*¹, *d*² which serve as brackets for the stub shafts *c*¹ of the bevel-wheels *c*. The shafts *c*¹ form part of the crank arms *c*², each of which drives the corresponding bevel wheel *c* by means of an eccentric boss *c*³ on which the bevel wheel is mounted. The two frames *d* are connected together by stays *d*³ 70 having shoulders (Figs. 2 and 3) which hold the two frames *d* at a fixed distance apart, and penetrate at each end with a slight amount of friction in their bearings up to the level of the teeth of the bevel wheels *b*¹. 75 In order to avoid displacement of the satellites *c* either under the force transmitted or under the action of centrifugal force, shafts *c*² are held in position on the stays *d*¹ by means of abutments *c*⁴ having ball bearings 80 held in place by rings *c*⁵ in two parts and fixed on the shafts *c*, by means of grooves *c*⁶ formed in the latter and in which engage the said rings.

The crank-arms *c*² are connected by rods *e* 85 to pistons *e*¹ working in pairs in the cylinders *f* in which the two pistons of each pair reciprocate in opposite directions, that is, in each cylinder the two pistons move simultaneously either toward or away from each other. Each of the cylinders *f* engages, by means of its two ends, with a bearing formed in the end plates *d*⁴ of the frame *d*, and is provided at the center with a tapped boss *f*¹ (Fig. 3) for the ignition plug, as 90 well as with a pipe *f*² through which the explosive mixture is sucked into the cylinder between the two pistons. The pipes *f*² of all the cylinders are held by means of screwed sleeves *f*³ in a drum *f*⁴ with which 100 they form one piece. This drum consists of two flanges held together by bolts *f*⁵ (Fig. 3) and incloses, by means of the shoulder *g* a hollow drum *g*¹ mounted on the central shaft *a*. The drum *f*⁴ turns with a certain 105 amount of friction on the shoulder *g* and bears against the packing leathers *g*², *g*³, thus making a tight joint.

The ends of the radii of the frame d engage with the heads h , which receive the ends of the frame in grooves h^1 . The heads h extend beyond the ends of the cylinders 5 toward the centers of the latter so as to form an oil chamber h^2 about the latter, the purpose of which will appear later. The heads h are held in place by endplates i which themselves engage, by means of 10 grooves i^1 , the radii of the frame d and are firmly fixed to each of these radii by means of a kind of circular key i^2 , which latter, after the member i is placed in position, is manipulated by means of a key introduced 15 through the aperture i^3 , the said key forming a pinion corresponding to the gearing of a rack fixed to or formed on the rim of the circular key i^2 .

The engine casing comprises two closed 20 end sections i . One of the casing sections, or if desired, both of these casing sections are provided each with a sprocket wheel, pulley or toothed wheel j which can either be in one piece therewith or can be fixed thereto 25 in any suitable manner so as to revolve about the shaft a on a bush j^1 and to transmit motion from the motor to the machine to be driven.

In the motor shown in the drawing as an 30 example, as the bevel wheel b^1 is of a diameter equal to four times that of the satellite wheels c , the consequence is that for one revolution effected by one of these latter around the large wheel b^1 it will turn four 35 times about its own axis, and that each cylinder f will therefore, for each revolution of the entire motor about the fixed shaft a , give an effect equal to twice that of the four-stroke cycle of an ordinary explosion engine.

40 In consequence the suction period of each cylinder f will correspond to one eighth of the circumference. In order to provide for the suction of the explosive mixture through pipe f^2 the shoulder g of the drum g^1 must 45 have two apertures g^4 diametrically opposite each other and each corresponding to an eighth of its circumference. Each of the pipes f^2 will register therewith successively, while the drum g remains, while the engine 50 is running, fixed on the shaft a through the hollow interior of which the gas or explosive mixture coming from the carburetor is fed through the apertures a^1 .

The carburetor (not shown) is fixed on 55 the left hand end (Fig. 1) of the hollow shaft a which serves as a feed pipe, and supplies gas to the cylinders f , under the control of a speed regulator h . The latter actuates a distributing valve k^1 , the rod of which is 60 constantly urged toward the right (Fig. 1) by a spring k^2 . This spring can be adjusted at will by means of the bearing k^4 sliding along a screwed rod k^5 , passing through a boss k^6 . The rod k^5 terminates in a square 65 k^7 adapted to receive an adjusting key by

means of which the rod k^5 can be rotated so as to increase or diminish the tension of the spring. The governor k acts upon the valve k^1 against the action of the spring k^2 through the intermediary of racks k^{10} fixed on a circular bracket k^8 . The latter carries rolls k^9 which move in a groove in a ring k^{10} , and the latter, by means of a diametral shaft k^{11} sliding in two slots k^{12} in the shaft a , actuates the spindle k^2 of the distributing 70 valve. 75

When in operation the valve k^1 is constructed and adjusted in such a manner that, when the speed of the motor exceeds the normal, the valve moves from right to left (Fig. 1) under the action of the governor so as to close gradually, first the right hand ports a^1 (Fig. 1) thereby gradually cutting off half the supply of gas to the cylinders f . It then gradually closes the left hand ports a^1 (Fig. 1) so as to cut off the other half of the supply of gas, and opens in inverse proportion a direct supply of air through the ports a^2 . This continues until the valve k^1 having completely closed the ports a^1 opens 80 the ports a^2 to their fullest extent, so that now only air is admitted to the cylinders f . By moving the valve to its extreme rearward position (to the right in Fig. 1) all admission is cut off and a braking action is 85 obtained from the motor cylinders. 90

For ignition purposes a magneto is provided consisting of a fixed induction ring l having high and low tension coils and suitably supported by the shaft a , about which move two pairs of permanent magnets l^1 , l^2 , revolving with the drum f^4 to which they can be fixed in any suitable manner, or they can be driven in any other manner by the rotary movement of the motor. One of the terminals of the magneto is connected to the metal of the motor; the other is connected to two diametrically opposite studs m mounted on an ebonite ring m^1 . The latter is mounted with friction on the shaft a and can be 100 moved angularly around said shaft in any suitable manner so as to advance or retard the ignition. A contact m^2 is fixed for each cylinder f in a circular ebonite frame m^3 attached to the flange of the drum f^4 and consequently turns therewith. This contact is connected to the ignition plug of the corresponding cylinder and passes in front of one of the studs m at the exact moment when ignition should take place in the cylinder. It 105 is obvious that the commutator for the ignition can be arranged differently to the manner just described and that it is only described and shown in the drawings by way of example. 110

When the engine is running, the cylinders turn around the central shaft a owing to the rolling action of the satellites (rotated by the action of the pistons e^1 on the crank arms e^2) on the wheels b^1 , and thus act as a 115 120 125 130

flywheel, while they cool themselves by their rapid movement through the air.

Supposing the motor turns normally in a clockwise direction (Figs 2 and 3), in order 5 to reverse its direction of rotation it will be sufficient to displace the suction ports g^4 one eighth of a revolution in the direction of motion. For this purpose the drum g^1 is provided with two arcs n having rack-teeth 10 and engaging one on one side and the other on the opposite side with the toothed extremities of a diametral shaft n^1 on the center of which is keyed a helicoidal wheel n^2 driven from a worm n^3 . The latter is held 15 in the longitudinal direction by the two abutments n^4 of the small frame n^5 , and can be actuated by the rod n^6 terminating in a square n^7 for the reception of a crank. By this means motion in one direction or the 20 other can be transmitted to the shaft n^1 and thence through the racks n to the drum g^1 . Abutments can be provided to limit the extent of movement of the drum. Similar 25 mechanism to that used to move the drum g^1 angularly could be used for instance to rotate the ring m^1 about the shaft a for the purpose described.

The spent gases exhaust in each cylinder 30 at the end of the stroke of the pistons e^1 through orifices f^10 which are uncovered by the pistons at the end of their outward strokes.

Lubrication is effected by double-acting 35 oil pumps o , one of which is mounted on the end-plate d^4 of each of the frames d and draws in oil continuously through valves o^1 (by means of piping not shown). The oil 40 is discharged by the pump through the ports o^2 into the farthest recesses of the frame d . behind the stays d^2 , whence it escapes either 45 through ducts provided in the shafts c^1 , Fig. 1, or past the rubbing surfaces of the engine under centrifugal force, thus constantly lubricating all parts during its passage.

The oil pumps o can be driven by means 50 of a toothed rim or ring o^3 fixed on the shaft a and engaging with a toothed wheel o^4 whose shaft carries a worm o^5 engaging with a worm wheel o^6 (Fig. 2) revolving on a fixed shaft o^7 . The wheel o^6 carries an eccentric pin o^8 on which are pivoted the connecting rods o^9 which transmit motion to the pump pistons o^{10} in the pump body. 55 The suction valves o^1 are placed in the bottoms of the body of the pump o , through which valves the oil is sucked into the pump cylinders o and discharged through the valves o^2 to the parts to be oiled and to the 60 recesses in the frame d .

The action of the motor will be easily understood after the above description without further explanation.

It is obvious that the invention is not 65 strictly limited to the arrangement shown

and described above since it is evident that certain modifications could be made as may appear necessary or expedient. For instance if necessary in the case of large cylinders a compression-relief valve could be fitted which would open some instants before the compression stroke of the cylinders. 70

I claim:

1. In an engine, the combination of a fixed central shaft; oppositely disposed casings revolvably mounted on said shaft; a frame mounted within each of said casings and surrounding said shaft; said frames having the casings secured thereto; a plurality of bars disposed parallel with the casings and connecting said frames; a plurality of cylinders disposed parallel with the shaft mounted on said casings; a transmission gearing comprising intermeshing pinions mounted on said shaft and casings; 80 and pistons operable in said cylinders connected with said transmission gearing for imparting rotation to the casings; substantially as described. 85

2. In an engine, the combination of a central shaft; oppositely disposed casings revolvably mounted on said shaft; a frame mounted within each of said casings and secured thereto; a plurality of cylinders carried by said casings and disposed parallel 95 with the shaft; a pair of pistons operable in each of said cylinders; a pair of bevel pinions mounted on said shaft; satellite gears connected with said pistons and meshing with said bevel pinions for imparting 100 rotation to the casings; radially disposed stub shafts journaled within and carried by said frames, and on which said satellite gears are mounted; and means for charging said cylinders, substantially as described. 105

3. In an engine, the combination of a fixed central shaft; oppositely disposed casings revolvably mounted on said shaft; a frame mounted within and secured to each of said casings; a plurality of cylinders disposed 110 parallel with the central shaft, and having the ends thereof engaging with and supported by said casings and said frames; a plurality of bars disposed parallel with and between said cylinders, said bars connecting 115 said frames; pistons operable in each of said cylinders; and a transmission gearing comprising intermeshing pinions mounted on said shaft and said casings and connected with said pistons to impart rotation to the 120 casings, substantially as described. 125

4. In an engine, the combination of a fixed central shaft; a pair of oppositely disposed casings revolvably mounted on said shaft; an annular frame secured to each of said casings and surrounding the shaft; said frames comprising each a plurality of radially disposed bars connected by cross bars; a plurality of cylinders disposed parallel with the central shaft and carried by said cas- 130

ings; a pair of bevel pinions mounted within the casings on said shaft; pistons operable in each of said cylinders; a plurality of satellite gears connected to be actuated by 5 said pistons and meshing with said pinions; radially disposed stub shafts on which said satellite gears are mounted; said stub shafts being journaled on the connecting cross members of said frames; said intermeshing 10 gears and pistons operable to impart rotation to said casings; and means for charging said cylinders, substantially as described.

5. An explosion engine comprising a plurality of motor cylinders, a central fixed 15 hollow shaft having fuel ports, said motor cylinders being adapted to rotate about said fixed shaft, said cylinders having fuel admission ports adapted to register at the correct intervals with the fuel supply ports 20 in said hollow shaft, a valve sliding within said shaft to control said fuel supply ports, said hollow shaft having air supply ports, and means actuated by the engine to move

said valve to control said fuel and air supply ports in the manner described. 25

6. In an internal combustion engine, the combination of a fixed central and tubular shaft; a casing journaled to rotate on said shaft; cylinders mounted on said casing; a beveled gear wheel fixedly mounted on said shaft; pistons mounted to work in said cylinders; driving connections between said pistons and said beveled pinion, whereby to rotate the casing through said pistons; apparatus associated with said tubular shaft 30 for charging said cylinders with fuel; a valve mounted in said shaft for controlling the fuel supply to said cylinders; and a centrifugal governor associated with said casing 35 operable to automatically actuate said controlling valve, substantially as described. 40
